CHILD'S CLIMBING DEVICE

Eugene E. Epstein, 930 Lake Ave., Fort Wayne, Ind.

Filed Sept. 19, 1958, Ser. No. 52,699

Term of patent 14 years

(Cl. D34—5)

Fig. 1 is a view in perspective of my new child's climbing device; the broken line showing of a child is for illustrative purposes only;

Fig. 2 is a front view thereof; and

Fig. 3 is a top plan view thereof.

I claim:

The ornamental design for a child's climbing device, as shown and described.
